No. 872,335.

PATENTED DEC. 3, 1907.

C. A. FOSTER.
SCAFFOLDING SUPPORT.
APPLICATION FILED AUG. 20, 1908.

UNITED STATES PATENT OFFICE.

CHARLES A. FOSTER, OF OAKTOWN, INDIANA.

SCAFFOLDING-SUPPORT.

No. 872,335.

Specification of Letters Patent.

Patented Dec. 3, 1907.

Application filed August 20, 1906. Serial No. 331,322.

To all whom it may concern:

Be it known that I, CHARLES A. FOSTER, a citizen of the United States, residing at Oaktown, in the county of Knox and State of Indiana, have invented a new and useful Improvement in a Scaffolding-Support, of which the following is a specification.

This invention relates to scaffolding supports and more particularly to adjustable supports adapted to be used by plasterers or paperhangers when working the upper portion of the wall, of the ceilings of a room, the object being to provide a support which can be readily moved from place to place and one which can be easily and quickly adjusted so as to suit the height of the room.

Another object of my invention is to provide the support with clamping means for securely locking the supporting beam there-

on without any danger of it coming off.

This invention consists of the novel features of construction hereinafter fully described and pointed out in the claims.

In the drawings forming a part of this specification:—Figure 1 is a side elevation of my improved scaffolding support. Fig. 2 is a section taken on lines 2—2 of Fig. 1. Fig. 3 is a section taken on lines 3—3 of Fig. 2. Fig. 4 is a section taken on lines 4—4 of Fig. 2. Fig. 5 is a perspective view of the fork detached. Fig. 6 is a detail sectional view of the tubes illustrating my improved locking means. Fig. 7 is a perspective view of the locking member detached. Fig. 8 is a detail perspective view of the tube showing my improved supporting members in place. Fig. 9 is a perspective view of the supporting member detached. Fig. 10 is a section taken on lines 10—10 of Fig. 1.

In the drawings A indicates a base having feet A' and provided with a central threaded opening formed therein, in which the threaded end of a tube B is recessed forming a vertical standard which is provided with spaced

key hole slots B'.

A tube C is adjustably mounted in the tube B by a key D, provided with lugs D' at its ends, which passes through the slots B' and corresponding slots C' formed in the tube C and securely lock the tube together. A stem E is secured in the upper end of the tube C provided with an enlarged forked head E' having a set screw E² extending through one of the prongs of the fork adapted to engage a supporting beam F arranged therein and securely hold it in place. A sleeve G is

adjustably mounted on the tube B by a set screw G' provided with an apertured ear G² over which the forks of a head H is pivotally mounted which is provided with a threaded socket in which one of the threaded ends of a tube I, forming a supporting arm, is secured. The other end of the tube is secured in a threaded socket formed in a head J, which is provided with a jaw J', having a transverse tooth J² adapted to engage one side of the beam F. A slot is formed in the angle portion of the jaw in which the angle apertured portion of the jaw K is pivotally mounted on a pin K', which is also provided with a transverse tooth K² adapted to engage the other side of the beam. The jaw K is provided with a handle K³ having an upwardly projecting pin K⁴ carrying a chain K⁵, adapted to extend around the head J, and securely lock the jaws K to the beam F.

A V-shaped supporting member L' provided with a head L' is adapted to be secured in one of the key hole slots B' of the tube B, adapted to receive the beam F so that the scaffold can be supported below the top of the tube B when desired.

From the foregoing description it will be seen that I have provided a very novel support for supporting the scaffold so that it can be quickly adjusted when desired and one which will be very rigid in use so that all danger of the same turning over is prevented.

Having thus fully described my invention, what I claim as new and desire to secure by Letters Patent, is:—

1. In a device of the kind described the combination with a base provided with a standard, of a supporting member adjustably mounted in said standard, a sleeve adjustably mounted on said standard, and an arm pivoted to said sleeve, a head secured to said arm provided with a fixed jaw and a pivoted jaw mounted on said head for the purpose described.

2. In a device of the kind described the combination with a base provided with a threaded opening, of a threaded tube secured in said opening provided with key hole slots, a tube arranged in said tube provided with corresponding slots, a key passing through said slots, a stem mounted in the smaller tube provided with a forked head provided with clamping means, a sleeve mounted on the tube carried by the base, provided with an apertured ear, a head pivoted to said ear provided with a threaded

socket, a tube secured in said socket, a head secured to the end, said tube provided with a fixed jaw, a jaw pivoted to said head, and means carried by the pivoted jaw for locking it to the head for the purpose described.

3. In a device of the kind described, the combination with a base having a hollow cylindrical standard mounted thereon, of a tube adjustably mounted in said standard, both of said standards and said tube being provided with registering key-hole slots, and a supporting bracket adapted to be inserted in said keyhole, slots for supporting a bearing below the top of said standard.

4. In a device of the kind described, the combination with a base provided with a hollow standard, of a tube mounted in the stand-

ard provided with keyhole slots registering with similar slots in said standard, a sleeve adjustably mounted on the standard, an arm pivoted at one end to said sleeve and provided at its other end with a head having a fixed jaw and a jaw carrying locking means, pivotally U-shaped brackets having an angled head formed on the end thereof, said head being adapted to be inserted, in said keyhole slots, securely locking said bracket in a suspended position for the purpose described.

CHARLES A. FOSTER.
